UNITED STATES PATENT OFFICE.

CURTIS C. WALLACE, OF ESTELLINE, TEXAS.

ENVELOP.

1,126,596.

Specification of Letters Patent.

Patented Jan. 26, 1915.

Application filed December 13, 1913. Serial No. 806,571.

To all whom it may concern:

Be it known that I, CURTIS C. WALLACE, a citizen of the United States, residing at Estelline, in the county of Hall and State 5 of Texas, have invented new and useful Improvements in Envelops, of which the following is a specification.

The invention relates to envelops, and has for an object to provide an envelop which, 10 when once sealed, cannot be opened or fraudulently tampered with without in some manner mutilating or defacing the envelop.

The invention contemplates, among other features, the provision of an envelop of a 15 simple construction and which, after mail matter has been received therein, can be so sealed that the envelop cannot be opened and the mail matter fraudulently removed without so defacing the envelop or mutilating 20 the same that the fact that it has been fraudulently tampered with will be apparent to the party for whom the mail or contents of the envelop is intended.

In the further disclosure of the invention 25 reference is to be had to the accompanying drawings, constituting a part of this specification, in which similar characters of reference denote corresponding parts in all the views, and in which:

30 Figure 1 is a rear elevation of the envelop, showing the same open and before sealing; Fig. 2 is a vertical transverse sectional view taken through the envelop after the same is sealed; Fig. 3 is a horizontal sectional view 35 taken through the envelop after the same is sealed; Fig. 4 is a perspective view of the member of the sealing flap, removed from the said flap; and Fig. 5 is a perspective view of the button.

40 Referring more particularly to the views, I disclose an envelop 10 consisting particularly of a body 11 adapted to receive suitable mail matter and having a sealing flap 12, which, folded upon the body 11, is 45 adapted for the purpose of closing the same. In order to insure the proper sealing of the flap 12 to the body 11 I employ a lock member 13 and a seal member 14, the lock member 13 being adapted to be applied to the body 11 of the envelop and the seal member 50 14 being adapted to be applied to the flap 12 whereby, when the flap 12 is arranged in closed position, the seal member, engaging the lock 13, will readily secure the sealing

flap 12 relatively to the body of the envelop 55 so that the envelop cannot be opened without partially mutilating the same. To this end I form the lock member 13 of a back plate 15 provided with a simple opening 16 and carrying a plurality of spaced 60 spring-like members 17 which extend across the opening 16. The back plate 15 is applied to the inside of the body 11 and is secured thereto by glue so that the opening 16 will register with an eyelet 18 carried by a 65 front plate 19 and projecting through an opening 20 in the body 11, said opening 20 being in registration with the opening 16.

The seal 14 consists, more particularly, of a button 21 carrying a plurality spaced 70 plates 22 and between which is interposed the flap 12, the said button 21 being pressed or swaged so that it will be securely held upon the flap by the plates 22 to which it is rigidly connected. The button includes an 75 annular groove 23 and after the mail matter has been placed in the envelop 10, the flap 12 is folded into closed position and the button 21 is adapted to be pressed through the eye 18 and into engagement with the spring-like members 17, the said spring-like members being adapted to be snapped into the annular groove 23 of the button, thus rigidly securing the seal 14 to the lock member 80 13 and holding the sealing flap 12 in closed position. It will be apparent that with this construction the sealing flap cannot be 85 opened for the purpose of removing the mail matter from the envelop, without defacing or mutilating either the body of the 90 envelop or the sealing flap, and thus it will be possible for persons receiving the mail matter to instantly tell whether the same 95 has been tampered with or not.

From the foregoing description it will be 100 apparent that the device described is of a simple and durable construction, consists of few parts and is particularly adaptable for use on envelops made of heavy paper.

Having thus described my invention, I 105 claim:

In an envelop, the combination with an envelop body having a sealing flap, of a back plate arranged inside of the body and secured thereto, said back plate having an 105 opening, a front plate on the exterior of the body and provided with an opening in registration with the opening in the back plate,

a sealing member on the sealing flap and adapted to project through the opening in the front plate and extend into and through the opening in the back plate when the sealing flap is closed, a head on the sealing member, and a spring-like member lying within the plane of the back plate and adapted to engage the head of the sealing

member to secure the sealing member against removal from the back plate. 10

In testimony whereof I affix my signature in presence of two witnesses.

CURTIS C. WALLACE.
